UNITED STATES PATENT OFFICE.

LLOYD JONES, OF PITTSBURGH, PENNSYLVANIA.

METHOD OF AND APPLIANCE FOR USE IN ROLLING-MILL OPERATIONS.

Application filed March 24, 1921. Serial No. 455,067.

To all whom it may concern:

Be it known that I, LLOYD JONES, residing at Pittsburgh, in the county of Allegheny and State of Pennsylvania, a citizen of the 5 United States, have invented or discovered certain new and useful Improvements in Methods of and Appliances for Use in Rolling-Mill Operations, of which improvements the following is a specification.

10 My invention relates to improvements in methods of and apparatus for preventing distortion of elongate articles incident to the cooling of the articles after delivery from the forming instrumentalities. It is particularly applicable to the production of 15 rolled articles of metal.

Elongate rolled articles of metal, such for example as steel beams and rails, come from the final pass of the rolling mill at 20 a temperature very considerably higher than atmospheric, and they lie on cooling beds until gradually they come to atmospheric temperature. In cooling such articles shrink, and in shrinking are liable to distortion such 25 in degree as often to be prejudicial to their intended use. This is peculiarly true in the case of articles of irregular or unsymmetrical cross-sectional form, such, for example, as the familiar railroad rails.

30 Various expedients have been resorted to, to overcome this difficulty in manufacture. One such expedient is so to roll the article that on delivery from the final roll pass it shall be oppositely curved to the shape to 35 which otherwise it would by thermal contraction be distorted; this with the end in view that thermal contraction shall bring it ultimately to the desired straightness. This rolling to opposite curvature is called cambering. It is, however, but imperfectly successful, for the degree of distortion is not 40 capable of accurate predetermination; so cambering though in some degree curative, does not in practice effect complete cure.

45 Another expedient is to pass the article when cold through straightening rolls, in which the article is bent to a degree exceeding the elastic limit, at which a permanent set takes place. This operation has inherent 50 disadvantages, and, besides, the practice of it involves the use of additional machinery, and the expenditure of additional time and labor.

55 My invention consists essentially in holding the article under tension during the time

of its cooling, to the end that thermal contraction may not be effective to distort it.

The invention is illustrated in the accompanying drawings, in which Fig. I is a view in vertical section through the cooling bed of a rolling mill, and resting upon this cooling bed a rolled article is shown in elevation, held under tension. Fig. II is a similar view, showing means for accomplishing the same end. In this figure my invention 60 in its general aspect is illustrated. Fig. III is a diagrammatic view showing mechanism wherein my invention in part resides, this mechanism being here shown in its organization with other material-handling parts. 65 Figure III^a is a fragmentary view, partly in elevation, partly in vertical section, of a portion of the structure shown in Figure III. Fig. IV is a plan view of a mill assembly, illustrating more fully, how my invention may be organized; and Fig. V is a plan view of the cooling tables on the discharge side of a rolling mill, in which my invention in greater elaboration is present and is adapted to economy. 70

Referring first to Fig. I, 1 indicates a length of rolled material lying on a table 2, in position such as it occupies immediately on coming from the finishing pass of the rolling mill,—or perhaps from shears stationed 85 at the delivery side of the final roll pass. On this table 2 the material grows cold. Arranged for co-operation with table 2 is a pair of cams 3, so situated that they may engage at opposite ends the length of rolled 90 material brought to position beneath them, and may clamp the length of material at its opposite ends securely to the table. As the material so clamped grows cold, and in cooling shrinks, tendencies to distortion are resisted and overcome by the tension set up 95 between the two points of gripping, and the consequence is that the length of material when cold is straight. Indeed, by such means small deviations from straightness 100 present in the material while hot will correct themselves.

In Fig. II the length of material 1 resting on table 2^b is shown to be gripped at opposite ends by tongs 4, 4. One pair of 105 tongs is anchored to the table; the other is carried on the stem of the piston of an hydraulic cylinder 5. The hydraulic cylinder is in communication with an hydraulic accumulator 6. In this case the ten- 110

sion set up by the cooling and contraction of material 1 is in some degree effective to draw the tongs carried by the piston of cylinder 5 from left to right; but correspondingly as this tendency expresses itself, it is met by the pressure exercised upon the piston from the accumulator 6, and this countervailing stress suffices, to prevent the distortion already dwelt upon, otherwise incident to cooling. The result is, as before: prevention of distortion under shrinkage of the length of material 1, but as will be perceived provision is found in the accumulator for limiting the degree of tension to which the cooling article is subjected. It would be possible in the practice of my invention to mount both pairs of tongs on the stems of hydraulic pistons; but in usual practice there would be no advantage in this duplication.

As shown in Figs. III and III^a, a rotary drum 2^a, is equipped peripherally with a large number of pairs of clamps between which successive lengths of material are secured to extend in a direction longitudinal of the drum. In Fig. III the twenty-eight small circles 5 arranged about the periphery of the drum serve to indicate diagrammatically in end elevation a succession of such hydraulic cylinders as are shown in Fig. II, and it will be understood that the drum here shown is equipped with twenty-eight pairs of clamps, such as that illustrated in detail in Fig. II. It will be understood too that the drum 2^a of Fig. III might instead be equipped with pairs of clamps such as shown in Fig. I. Figs. III and III^a show the peripheral cylinders 5 on drum 2^a to be connected with an axially situated manifold 14 and through this manifold with an accumulator 6 of the character already described.

A run-out trough 7 brings the lengths of hot material to position adjacent drum 2^a, and from the trough successive lengths are picked up and carried by the drum as it rotates, through a path defined by its periphery. At a suitable point in the path the clamps are released and the lengths of material escape down skids 8 to a run-out or delivery table 9. The provision of valve control for properly timed application of and relief of hydraulic pressure to cylinder 5 as the drum 2^a rotates is indicated at 15 in Figure III^a. The showing is diagrammatic. It will be understood that such a valve or its equivalent, accessible for automatic operation, will be provided for each cylinder 5.

The size of drum 2^a and its rate of rotation and the relative positions of trough 7 and of skids 8 to it will be so determined that the drum will pick up the successive lengths of material as rapidly as they are produced, and also that the time interval during which a length of material advancing upon the turning drum passes from trough 7 to skids

8 shall be sufficient, under the conditions obtaining, to allow the material to cool beyond the degree of temperature at which it takes permanent set, before delivery to skids 8.

In Fig. IV a mill lay-out is indicated, with the apparatus of my invention suitably located with respect to the whole. The roll stands of the finishing mill are indicated at 10; the run-out trough 7 leads from the ultimate roll pass to the cooling table. At a convenient point intermediate the length of trough 7 stands a hot saw 11, by means of which the newly rolled material is cut to desired lengths on its way to the place of cooling. Adjacent trough 7 at its further end, and in the position relative thereto more fully shown in Fig. III, stands the rotary drum 2^a, to which the lengths of newly formed and still hot material are applied, and upon which they are borne until they have cooled beyond the point of permanent set. From drum 2^a the material passes over skids 8 to the delivery table 9 along which the now cooled lengths of material advance to the point of delivery. A cold shear is indicated at 12, in the line of advance of material from table 9, and beyond the shear the cold and trimmed material is received on table 13. At 6 is diagrammatically shown the hydraulic accumulator (cf. Figs. II, III, and III^a) which, it will be understood, may be brought into communication with each of the cylinders 5 upon drum 2^a, and so made effective, to impose the requisite tension upon each length in turn of cooling material. It will of course be understood that the valves 15 may be automatically shifted to discharge the articles successively and at the proper time from drum 2^a to skids 8.

Fig. V shows an assembly for a mill in which heavier sections are rolled—such, for example, as railroad rails. The roll stands of the finishing mill are indicated at 10^a. At suitable intervals along the run-out trough 7 is arranged a plurality of hot saws 11, by which newly rolled material may be rapidly severed into a plurality of lengths. Correspondingly, the number of drums 2^a is increased, each with its set of skids 8 leading to delivery table 9. The table 13 may be enlarged to care for the more rapidly produced material. An hydraulic accumulator 6 is indicated, which may be made effective upon all of the hydraulic cylinders of all of the drums.

I claim as my invention:

1. The method herein described of preventing distortion of the rolled product of a hot mill which consists in holding the product yieldingly under tension while cooling progresses.
2. In combination with a hot mill, means for holding the rolled article yieldingly under tension as it cools.

3. In combination with a hot mill, means for holding the rolled article yieldingly under tension as it cools, said means including a clamp borne on the stem of the piston of 5 an hydraulic cylinder, together with an hydraulic accumulator in communication with said cylinder.
4. In combination with a hot mill, a rotary drum arranged on the delivery side of 10 said mill, said drum being provided with pairs of clamps adapted to engage at opposite ends a plurality of rolled articles delivered hot from the mill and to sustain articles so engaged during cooling.
5. The method herein described of obtaining from a hot mill a straight rolled product which consists in securing the product at two relatively remote points against contraction by a resisting force less in value than the contractile strain set up within the 20 article in cooling to atmospheric temperature.

In testimony whereof I have hereunto set my hand.

LLOYD JONES.
